WINDOW REGULATOR

Clifford C. Jackson, Detroit, Mich., assignor to
 Chrysler Corporation, Highland Park, Mich., a
 corporation of Delaware

Application November 2, 1950, Serial No. 193,709

11 Claims. (Cl. 268—124)

1

This application relates to panel regulators, particularly to electrically operated regulators for window panels.

A feature of the present invention resides in the provision of a power-operated window regulator which will easily and noiselessly raise and lower a window, particularly a window of an automobile body.

With the advent of the wide type of automobile body, it is now extremely difficult for a driver to raise and lower the window on the right hand side. The window regulator handle is beyond his reach when he is in the ordinary posture, and in order to grasp it he has to lean to an extreme position over to one side, in which extreme position his driving may be interfered with.

According to another feature of the invention, a window regulating mechanism is provided which is mounted to the supporting structure for the glass run at a minimum of fixed points, notably one, thereby resulting in a simple installation and removal of the mechanism. Moreover, only two points as the total number of connection points are contemplated for the mechanism, the mechanism only necessarily having to be connected to one point on the movable window panel in addition to the aforesaid one fixed point which serves as reference point from and toward which the panel moves.

According to still another feature, a window regulator is provided in which there are employed no tracks, guides or cross-heads for the mechanism and no attendant lubrication problems connected therewith inasmuch as a pin joint is the sole type joint employed.

According to yet another feature of the invention, a window regulator mechanism is provided which is completely elastically supported by elastic material resulting in an installation which is insulated against noise and vibration.

According to a further feature, a regulator mechanism is provided in which the joints used are pivot joints known mechanically to introduce but a minimum of friction as contrasted with other conventional joints incorporating relatively sliding parts for example.

According to still a further feature, provision is made for the satisfactory operation of a window lift mechanism not involving expensive and complicated controls like limit switches.

According to yet a further feature, a regulator mechanism is provided which utilizes an expandable and collapsible threaded strut having the threads thereof protected from condensate, dust, water, and like elements when the window is

2

closed, as under the circumstances outlined the threads are totally housed against exposure.

An additional feature of the invention lies in the provision of a lost motion connection between the power rotor and power shaft to give the power mechanism an opportunity to build up rotational inertia necessary for the impetus to break the window panel away from any wedged engagement or binding its extreme positions of travel.

According to another additional feature of the invention provision is made in a window regulator for a gradual transition from abrupt start and stop motion in the intermediate window positions of the window panel by virtue of the presence of an elastic mounting against which the mechanism may pivotally thrust.

Further features, objects and advantages will either be specifically pointed out or become apparent when for a better understanding of the invention reference is made to the following description taken in conjunction with the accompanying drawings in which:

Figure 1 is an elevation of the window regulator showing the parts in more than one position; and

Figure 2 is a section through the fixed pivot and lost motion connection between the power rotor and the power shaft.

In particular regard to Figures 1 and 2 of the drawings, the illustrated supporting panel 10 represents a conventional or other suitable support panel of a vehicle door, body window opening, or body partition structure. Supported by supporting panel 10 is one of a pair of glass runs 12 of general U-shaped configuration having corresponding legs 14 and 16 extending at angles from a base 18. Slidably received in glass run 12 is a window panel 20 which may be of glass having an edge thereof embraced between the legs 14 and 16 of the glass run. Window panel 20 is held by a metallic channel indicated at 22. Channel 22 has a bracket 24 carrying a pivot 26 forming a connection with a portion 28 of a link 30.

Affixed to panel 10 by welding, soldering or the like, is a nut 32 having a threaded bore 34 for reception of a fixed pivot structure. The pivot structure comprises a pivot pin 36, a washer 38, and a sleeve member 40 retained by washer 38 for limited rocking motion about pin 36. The mid portion 42 of the sleeve member 40 is reduced to provide an annular groove in which is received a strap 44 carrying a bumper 45 which may be of rubber or plastic material. The end portions of the sleeve member 40 are reduced to receive therearound bodies of elastic material 46. Bodies

46 are preferably of an elastomeric composition including rubber, elastic plastic, and elastic resin materials. A bellcrank 48 has a portion 50 adapted to receive a pivot pin 52 carried by link 30. A portion of bellcrank 48 provides an opening 54 embraceably surrounding an annular groove formed in the surface of one of the elastic bodies 46. Another bellcrank portion provides an opening 56 and a similar opening 60 is provided on a bellcrank companion member 58. Companion member 58 has a portion 62 apertured to be received about the other elastic body 46. Openings 56 and 60, as a pair, serve as gimbals for the reception of a pair of opposed projecting trunnions 64 carried by a motor casing structure 66. Motor casing structure 66 is provided with bearings such as rear bearing 68 in which are journaled the motor rotor and rotor shaft 69. A truncated tube 70 forms an outrigger part for the overall motor casing structure 66. Outrigger part 70 provides a plurality of bearings including a roller bearing 72 and a self lubricated sleeve bearing 74 which may be of a porous metal texture.

Journalled within the bearings 72 and 74 is a power shaft or sleeve 76 restrained against axial movement relative to outrigger part 70 by virtue of an annular shoulder 77 on the sleeve which engages the sleeve bearing 74 and also by virtue of the general resistance of roller bearing 72 to axial movement. Sleeve 76 has an end 78 presenting a pair of diametrically opposed lugs 80. A companion pair of lugs 82 is formed on a member 84 carried by the rotor shaft 69 for the motor rotor, not shown. Companion lugs 80 and 82 provide a lost motion connection between the motor rotor and the power shaft 76 later to be set forth more in detail. Sleeve 76 has a reduced inside diameter at the extremity 86 formed with threads for receiving a screwshaft 88 pinned at 89 to an extension portion 92 of link 30. Link portion 92 has formed therein an opening 94 receiving the hooked end of elastic member 96 which may be a spring. The opposite end of elastic member 96 is suitably anchored in the strap 44 secured around the girth of the fixed pivot sleeve 40.

A manually operated two-way switch 100 is connected to terminals on motor casing structure 66 for controlling the motor and the direction rotation of power sleeve 76. Switch 100 is connected to a power source 102 through a circuit breaker 104 which may be of the thermal type. The motor rotor, not shown, is preferably double-wound and in known manner is arranged to rotate in one direction or the other depending on the switch position of two-way switch 100. While the switch 100 is in its neutral position the motor is of course unenergized.

The operation of the device of Figures 1 and 2 is as follows. Link 30 and bellcrank 48 constitute a simple chain which may be straightened out or collapsed to bring movable pivot 26 and fixed pivot 36 relatively farther apart or closer together. Movable pivot 26 is constrained to purely rectilinear movement with respect to fixed pivot 36 owing to the constraint of glass panel 20 in the glass run guides. Broadly speaking, however, the movable pivot 26 may move through well defined curvilinear as well as rectilinear paths for the purposes of the operation of the window regulator mechanism. Spring 96 is so located and effective in tension to resist counter-clockwise movement of link 30 with respect to bellcrank 48 and thus has a tendency to attempt

to straighten out the joint at 52 between links 30 and 48 and resiliently counterbalance the weight of the window panel 20 and associated structure. Screwshaft 88 and its surrounding threaded sleeve 76 together constitute an expandable and collapsible strut, the effective change of length of which is controlled by relative rotation of one of the parts relative to the other. Screwshaft 88 is pinned at 90 to the link portion 92 and hence held effectively in restraint against relative rotation thereto. Power sleeve 76 is restrained by its bearings against axial movement relative to the pivot 64 and the outrigger part 70 of motor casing structure 66, but is nevertheless free for 10 swinging movement on pivot 64 and free for rotational movement in its bearings 72 and 74. The lugs 80 on the power sleeve 76 are engageable by companion lugs 82 for either direction of rotation for the motor rotor. The lost motion feature 15 made possible by these cooperating lugs permits the motor rotor to gain some speed prior to application of its torque to the power sleeve 76 with the benefit of the rotational inertia of the motor rotor in breaking away the window panel 20 and its related structure from any bind or wedging 20 which may result in service. Under influence of proper rotation of power sleeve 76, the screwshaft 88 may be caused to withdraw therefrom and assume a retracted position 88a relative to a new position 76a for the power sleeve. Accompanying the motion of the strut will be the co-ordinated movement of the link 30 in a counter-clockwise sense about pivot 52, with the result that the joint formed at 52 by links 30 and 48 will 25 flex away from the relatively straightened out position shown in full lines in Figure 1. Continued movement of flexure of the joint will bring the main portion of bellcrank 48 into the general horizontal position shown at 48a. At the same time the main portion of link 30 will approach a 30 relation of parallelism therewith such as to assume the position 30a wherein end portion 28 at position 28a engages the bumper 45. Since motor casing structure 66 is supported in gimbals 58 and 60 fixed relative to bellcrank 48, the trunnions 64 will move to a new position 64a and the motor casing structure will be attendant therewith and assume a general horizontal disposition 66a. Spring 96 will at the same time be elongated 35 somewhat and swung to the dotted line showing 96a. In its limited angular rocking movement the bellcrank 48 will generally be accompanied by the fixed pivot sleeve 40.

In the lowered position 22a of glass channel 22, the regulator mechanism has the stop 45 effective to prevent further movement. In its upper or raised position shown in Figure 1 in full lines, channel 22 and the glass panel structure may be stopped by engagement with the upper end of the window opening bounded by glass run 12. In the upper position, it is to be noted that the screwshaft 88 is substantially completely enclosed in the power sleeve 76 in a manner such that neither the internal nor the external threads of the threaded members 76 or 88 are exposed to the elements. Hence any dust, dirt, rain, or condensate present within the supporting structure 10 cannot find access to the threads or to the lubricant carried thereon.

In the course of an operating cycle of the regulator mechanism, manual switch 100 is moved out of its neutral position to complete a circuit between source 102 and one winding of the double wound rotor of motor structure 66. Rotor shaft 69 is arranged to be caused to rotate

counterclockwise according to Figure 2 and the power sleeve 16 similarly rotates to cause a withdrawal of screw shaft 88 owing to the threadable engagement of sleeve portion 86 therewith. Links 30 and 48 are accordingly permitted to move from the extended position of Figure 1 to a retracted or collapsed position for lowering window 20. Conversely, when manual switch 100 is operated to complete a circuit between source 102 and the other winding of the rotor of motor structure 66, the motor and power sleeve 16 rotate in the opposite direction to the direction aforesaid, and screwshaft 86 is caused to be threadably advanced through power sleeve 16 and the links 30 and 48 are caused to open up or extend. If the window 20 is forcibly detained from moving at a time when the motor of structure 66 is energized, the thermal circuit breaker 104 is arranged to open circuit the switch 100 and for a period to prevent re-energization of the motor until the circuit breaker 104 has had a chance to cool down. Thus if the motor is stalled due to an obstruction in the window opening or due to the panel 20 arriving at either one of its limits of travel, no damage will result to the motor windings even though switch 100 is not returned to neutral position in due course.

It will be observed that in either extreme of travel of the window regulator mechanism just set forth, the elastic bodies 46 are effective to take up the shock of abrupt stoppage of motion. The lost motion connection provided by lugs 80 and 82 will tend to compensate for and overcome any binding or jamming that may result at these extremes of travel. It is noted that in the intermediate positions of window panel 20, the elastic bodies 46 serve to take up the reaction thrust of the window regulator mechanism and to provide smooth starting and stopping movement.

Variations within the spirit and scope of the invention described are equally comprehended by the foregoing description.

What is claimed is:

1. A window regulator comprising a pivotally supported member having portions swingable through arcs, a window panel supported for sliding movement toward and away from the point of pivotal support of the member aforesaid, a link carried by a said swingable portion of the pivotally supported member and having one end connected to the window panel, complementary threaded members one within the other and each providing an outer end portion relatively separable with respect to the other outer end portion upon relative rotation of the threaded members, means mounting the respective outer end portions of the threaded members to the other end of the link and to a portion of the pivotally supported member for pivotal movement relative thereto and including a bearing journaling a certain of said threaded members for relative rotation relative thereto, and means for rotating said certain threaded member to change the angular relation between the link and pivotally supported member for causing the said one end of the link and the window panel to move relative to said point of pivotal support of the pivotally supported member.

2. A window regulator comprising a pivotally supported member having portions swingable through arcs, a window panel supported for sliding movement toward and away from the point of pivotal support of the member aforesaid, a link carried by a said swingable portion of the

pivotaly supported member and having one end connected to the window panel, complementary threaded members one within the other and each providing an outer end portion relatively separable with respect to the other outer end portion upon relative rotation of the threaded members, means mounting the respective outer end portions of the threaded members to the other end of the link and to a portion of the pivotally supported member for pivotal movement relative thereto and including a bearing journaling a certain of said threaded members for relative rotation relative thereto, and means for rotating said certain threaded member to change the angular relation between the link and pivotally supported member for causing the said one end of the link and the window panel to move relative to said point of pivotal support of the pivotally supported member and in combination therewith, an elastic member acting between said other end of the link and the point of pivotal support to oppose movement of the said link one end toward the latter.

3. A window regulator comprising a pivotally supported member having portions swingable through arcs, a window panel supported for sliding movement toward and away from the point of pivotal support of the member aforesaid, a link pivotally carried by a said swingable portion of the pivotally supported member and having one end pivotally connected to the window panel, complementary threaded members, one within the other and each providing an outer end portion relatively separable with respect to the other outer end portion upon relative rotation of the threaded members, means mounting the respective outer end portions of the threaded members to the other end of the link and to a portion of the pivotally supported member for pivotal movement relative thereto and including a bearing journaling a certain of said threaded members for relative rotation, and power means for rotating said certain threaded member to change the angular relation between the link and pivotally supported member for causing the said one end of the link and the window panel to move relative to said point of pivotal support of the pivotally supported member.

4. For use with reference to a supported pivot, a window panel guided to slide toward and away from the pivot, a pair of mutually interconnected links forming a chain having respective end portions thereof, one swingably connected at a single point to the window panel, and the other adapted to be pivotally carried by the supported pivot for swinging action thereabout, a pair of threadably engaged members forming a relatively expandable and collapsible strut element pivotally acting between points on the mutually interconnected links respectively and having the respective end portions thereof, one restrained against relative rotational and axial movement with respect to its corresponding link, and the other restrained against relative axial movement but free to rotate with respect to the other link, and power operated means mounted to said other link and drivingly connected to said other end portion of the expandable and collapsible strut element for rotating the end portions of the latter with respect to each other to cause a change in the relative angularity between links about their point of mutual interconnection.

5. For use with reference to a supported pivot, a window panel guided to slide toward and away from the pivot, a pair of mutually intercon-

nected links forming a chain having respective end portions thereof, one connected to the window panel, and the other adapted to be pivotally carried by the supported pivot for swinging action thereabout, a pair of threadably engaged members forming a relatively expandable and collapsible strut element pivotally connected at and acting between points on the mutually interconnected links respectively and having the respective end portions thereof, one restrained against relative rotational and axial movement with respect to its corresponding link, and the other restrained against relative axial movement but free to rotate with respect to the other link, and tensioned spring means connected to each of said links effective to resist increasing angularity between the links, the said points of pivotal connection of the strut member to the mutually interconnected links being spaced with respect to the point of mutual link interconnecting.

6. For use with an openable and closable panel for a window opening, a supported pivot toward and away from which the window is to move, a pair of links forming a chain having one end portion thereof swingably mounted to said supported pivot and the other end portion adapted for pivotal connection with the window panel for coordinating movement of the latter with change in relative angularity between links, a relatively expandable and collapsible strut element formed of a screw shaft having an end pivoted to one link and hollow sleeve means threadably receiving the screw shaft proper, the threads of said screw shaft being arranged in a manner such that when the strut element is fully collapsed the threads are protected from exposure by being substantially enclosed with the hollow of the sleeve means, motor casing structure pivoted to swing with respect to the other link and providing bearing means, and means arranged in drive transmitting relation journaled in the bearing means and including a motor rotor and the sleeve means and restrained against axial movement relative thereto.

7. For use with an openable and closable window panel for a window opening, a supported pivot toward and away from which the window is to move, a pair of links forming a chain having one end portion thereof swingably mounted to said supported pivot and the other end portion adapted for pivotal connection with the window panel for coordinating movement of the latter with change in relative angularity between links, a relatively expandable and collapsible strut element formed of a screw shaft having an end pivoted to one link and hollow sleeve means threadably receiving the screw shaft proper, motor casing structure pivoted to swing with respect to the other link and providing bearing means, means arranged in drive transmitting relation journaled in the bearing means and including a motor rotor and the sleeve means and restrained against axial movement relative thereto, said last named means further including a lost motion driving connection between the motor rotor and sleeve means.

8. For use with an openable and closable window panel for a window opening, a supported pivot toward and away from which the window is to move, a pair of links forming a chain having one end portion thereof swingably mounted to said supported pivot and the other end portion adapted for pivotal connection with the window panel for coordinating movement of the latter

with change in relative angularity between links, a relatively expandable and collapsible strut element formed of a screw shaft having an end pivoted to one link and hollow sleeve means threadably receiving the screw shaft proper, motor casing structure pivoted to swing with respect to the other link and providing bearing means, means arranged in drive transmitting relation journaled in the bearing means and including a motor rotor and the sleeve means and restrained against axial movement relative thereto, and a spring member connected to each link resiliently effective to oppose collapse of the chain.

9. For use with an openable and closable window panel for a window opening, a supported pivot toward and away from which the window is to move, said supported pivot having an elastic body therearound, a pair of links forming a chain having one end portion thereof swingably carried by the elastic body on said supported pivot and the other end portion being adapted for pivotal connection with the window panel for coordinating movement of the latter with change in relative angularity between links, a relatively expandable and collapsible strut element formed of a screw shaft having an end pivoted to one link and hollow sleeve means threadably receiving the screw shaft proper, motor casing structure pivoted to swing with respect to the other link and providing bearing means, and means arranged in drive transmitting relation journaled in the bearing means and including a motor rotor and the sleeve means and restrained against axial movement relative thereto.

10. 19. For use with a slidably openable and closeable, guided window panel for a window opening, a supported pivot toward and away from which the window panel is guidably arranged to slide in assuming respective opened and closed positions, a pair of links provided to form a chain between the supported pivot and the window panel and having an extended position corresponding to the closed position of the window panel and having a retracted position corresponding to the open position of the window panel, each said link having a body portion intervening between the respective opposite extremities thereof, the body portion of one said link being swingably supported by said pivot and said one link having one extremity thereof pivotally connected to the body portion of the other said link, the said other link having means for connecting one extremity thereof to the window panel, the opposite extremities of each of said links being commonly disposed in spaced relationship to the same side of a line passing through said supported pivot and said pivotal connection between links, and an expandable and collapsible strut element disposed between and swingably connected to the said opposite extremity of each of said links, said strut element having power means to operate the same and being pivotally mounted to a said opposite extremity of one link to form the just-described swingable connection for the strut element, said strut element further having a collapsed position corresponding to the closed position of the window panel and to the extended position of the chain and being of a bipartite construction formed of threadably engaged outer and inner parts, one of the said parts being drivingly connected to the power means with the threads of said inner part being arranged in such a manner that when the strut element is collapsed the

threads are protected from exposure by being substantially enclosed by the outer part.

11. Window regulating means for movable window panels and the like, comprising a supported pivot, a panel-connected mounting bracket and a pivot anchored thereto, a pair of articulated links one connected to one said pivot and one connected to the other said pivot, a first elongated part and a second hollow part receiving said first part therein, and a pivotally supported power unit disposed on one side of a reference line passing through said supported pivot and the point of articulation between the articulated links drivingly connected to one said part for rotating the same, the other said part having an end pivotally connected to one said link at a

point on the same side of the reference line as above described and being threadably engaged with said one part so as to be shifted longitudinally due to rotation of the latter for causing movement of the panel-connected mounting bracket.

CLIFFORD C. JACKSON.
